E. F. TECHMER

BUILDING CONSTRUCTION

Filed Nov. 22, 1926

UNITED STATES PATENT OFFICE.

EWALD F. TECHMER, OF CHICAGO, ILLINOIS.

BUILDING CONSTRUCTION.

Application filed November 22, 1926. Serial No. 150,100.

My invention relates to improvements in building constructions, and it consists in the combinations, constructions, and arrangements herein described and claimed.

5 An object of my invention is to provide a device for use with concrete ceilings by means of which suspension bars or rods for metal lath or similar ceiling material may be quickly and economically applied.

10 A further object is to provide a device of the type described in which the suspending means for the rods or bars are so arranged that, when the forms for the concrete have been removed, the suspending means will drop down into position to immediately receive said rods or bars.

15 A further object of the invention is to provide a metal form for housing the suspending means, this form being anchored in the concrete by means which also serves as a guide means for reinforcing rods, thereby facilitating the rapid and accurate placing of said reinforcing rods.

20 A further object is to provide metal forms which in themselves form a support for the reinforcing rods, thereby obviating the use of additional supporting members.

25 Other objects and advantages will appear in the following specification; and the novel features of the invention will be particularly pointed out in the appended claims.

30 My invention is illustrated in the accompanying drawings, forming part of this application, in which

35 Figure 1 is a side view of one of the metal forms, the wooden form upon which it is supported being shown in section,

Figure 2 is a sectional view along the line 2—2 of Figure 1,

40 Figure 3 is a sectional view through the concrete portion of the ceiling and the wooden form boards before they have been removed,

45 Figure 4 is an enlarged detailed view showing a portion of the concrete ceiling, the suspending means and the metal lath, the metal form and the anchor being shown in elevation,

50 Figure 5 is a view of a modified form of the device, and

55 Figure 6 is a diagrammatic view showing the staggered arrangement of the metal forms for supporting the reinforcing rods.

Referring now to the drawings, 1 indicates a concrete floor which is cast on a form such as a wooden form 2. This is supported

in any suitable manner, as by the supports 3. Carried by the form 2 are inverted metal troughs 4 which are spaced apart and which may be removed after the concrete is set. 60 Between these troughs, I place a series of cup-shaped metal forms like that shown at 5. These forms are the general shape shown in Figure 6. The tops 5^a are preferably flat. The sides have grooves 6 pressed therein and the bottoms have openings 7. Anchoring devices like that shown in Figure 2 are provided. These anchoring devices consist of a central bowed portion 8 which is within the form 5. The ends of this portion are prolonged and passed through the opening 7 and then are bent upwardly and lie in the grooves 6. Above the upper flat surface 5^a, these anchoring devices are bent outwardly 65 to form guide members 8^a. 70

75 Before the anchors are placed around the form 5, a suspending member 9 in the form of a loop is passed over one end of the anchor and over the central portion 8. This loop may have an elongated form as shown in Figure 4, or it may be of any suitable shape 80 to receive the particular member which it is designed to support. In Figure 4 I have shown the loop 9 as supporting a channel iron or bar 10. In this figure the loop is 85 elongated. In Figure 5 the opening in the loop may be circular to receive a circular rod or pencil 11.

In operation, the form boards 2 are erected, the troughs 4 placed in position, and the forms 5 are placed between the troughs. They are preferably arranged in two or more rows, as shown in Figure 6, the forms of each row being staggered with respect to the adjacent row. In order to hold the metal forms to the wooden form, I preferably drive a nail 12 down through the top of the form 5 so that there is no danger of displacing the form when the reinforcing rods are being placed or when the concrete is being poured. 90 95 100

With the metal forms arranged as shown in Figure 6, the reinforcing rods 13 are very easily applied. The flaring arms 8^a of the anchor form guide means so that it is only necessary to drop the rods 13 when the arms will guide them to the tops of the forms 5, where they rest. This obviates the necessity of having additional supporting means for the reinforcing rods. 105

When the forms 5 are applied and nailed to the wooden form 2, the movable suspending member 9 will be pushed up into the 110

position shown in Figure 2. When however, the concrete has set, and the form boards 2 are removed, the suspending member 9 will now drop down and will slide to the end of the bowed portion 8 and remain suspended. All that is necessary in order to hold the bars 10 or the pencil rods 11 is to pass them through the loop, as shown in Figure 4.

In constructions where there is considerable weight, it is advisable to use channel irons 10. The metal lath 14 may be wired or otherwise secured to the bars 10 or to the pencil rods 11, as shown at 15 in Figure 5.

When the form boards 2 are removed, it is not necessary to remove the nail 12. The latter, however, does not interfere with the suspending member 9, since it is placed toward one end and one side of the form 5, as shown in Figures 1 and 2. One nail is sufficient to hold the form in place, and it is an easy matter to take off the form boards since the nail is comparatively small.

The construction described above has a number of important advantages. As stated, it forms a means for supporting the reinforcing rods and for quickly placing them in position. It enables the forms 5 to be placed directly on the form boards 2, since the suspending member moves within the form 5 to permit it. It obviates the necessity of tying the bars or rods to the suspending member, but permits them to be thrust through the aligned loops, where they are held securely. The flaring outwardly of the arms 8^a serves the double function of guiding the reinforcing rods into their positions on the tops of the forms 5 and then, when the concrete has been poured, they have their normal functions of anchors for the suspending means 9.

I am aware that metal forms like that shown at 5 having suspending means is not broadly new, but ordinarily the lath or rods have to be secured to the suspending means by tying or in some other way and do not consist of loops through which the bars or rods may be thrust, nor do the forms serve

the purpose of supports for the reinforcing rods nor do the anchors serve as guides for putting the rods in place.

I claim:

1. A building construction, comprising a concrete ceiling having a plurality of cup-shaped metal forms embedded in the lower surface thereof, certain of said forms being in axial alignment, a U-shaped anchor for each form, said anchor having a central bowed portion disposed within the form, and angularly disposed guide portions above and to one side of the top of the form, and a suspending loop carried by said central portion.

2. A building construction, comprising a concrete ceiling having a plurality of cup-shaped metal forms embedded in the lower surface thereof, certain of said forms being in axial alignment, a U-shaped anchor for each form, said anchor having a central bowed portion disposed within the form, and angularly disposed guide portions above and to one side of the top of the form, and a suspending loop carried by said central portion, said loop having an opening for permitting an upward movement within the form or a downward movement to bring the loop below the lower edge of the form.

3. A building construction, comprising a concrete ceiling having a plurality of cup-shaped metal forms embedded in the lower surface thereof, certain of said forms being in axial alignment, a U-shaped anchor for each form, said anchor having a central bowed portion disposed within the form, and angularly disposed guide portions above and to one side of the top of the form, and a suspending loop carried by said central portion, said loop having an opening for permitting an upward movement within the form or a downward movement to bring the loop below the lower edge of the form and a lath suspending member arranged to be received and be suspended by the loops of certain of said aligned forms.

EWALD F. TECHMER.
